UNITED STATES PATENT OFFICE.

JAMES K. DARBY, OF CHILlicothe, Ohio.

PRESS-ROLL ARRANGEMENT FOR PAPER-MAKING MACHINES.

1,327,225.

Specification of Letters Patent.

Patented Jan. 6, 1920.

Application filed June 7, 1916. Serial No. 102,194.

To all whom it may concern:

Be it known that I, JAMES K. DARBY, a citizen of the United States, residing at Chillicothe, county of Ross, State of Ohio, have 5 made a new and useful invention in Press-Roll Arrangements for Paper-Making Machines, of which the following is a specification.

This invention relates to paper making 10 machines, and particularly to the press roll arrangement thereof.

The object of the invention is to provide a paper making machine which is simple in structure, and which reduces the amount of 15 space occupied by the present types of machines.

Further objects of the invention will appear more fully hereinafter.

The invention consists substantially in the 20 construction, combination, location and relative arrangement of parts, all as will be more fully hereinafter set forth, as shown by the accompanying drawing, and finally pointed out in the appended claims.

25 Referring to the drawing:—

Figure 1 is a diagrammatic view in elevation of the common type of Fourdrinier paper making machine.

Fig. 2 is a similar view of a similar structure embodying my invention.

Fig. 3 is a similar view of a modification of the structure shown in Fig. 2.

The same part is designated by the same reference numeral wherever it occurs 35 throughout the several views.

In the Fourdrinier type of paper-making machines, as diagrammatically illustrated in Fig. 1, it is customary to run the paper between a pair of rolls 1, of substantially equal 40 diameter, a second pair of press rolls 2, of substantially equal diameter, a third pair of press rolls 3, of substantially equal diameter, over a receiving roll 5, and on to the drying rolls of the machine. The paper is fed into 45 and carried past the respective press rolls on felts 6, operating over felt rolls 4. The action and purpose of the pairs of rolls 1, 2, 3, is to press out the water from the pulp sheet, which water, after being pressed out, 50 is sponged up by the felt carrier. It is obvious that the paper should pass between the pairs of rolls in order that the water may be pressed out of the pulp thereby. It is among the special purposes of my present 55 invention to provide means for pressing the paper so as to remove the water therefrom,

employing press rolls for this purpose, and to secure the usual or necessary number of press roll applications to the paper to expel or press out the water therefrom, while at 60 the same time greatly reducing the number of press rolls employed for this purpose, without altering the efficiency of the pressing action of the rolls, thereby reducing the space occupied by the machine, the weight 65 thereof, and the cost.

In Fig. 2 I show my invention as combining the pairs of press rolls 1 and 2 of Fig. 1, and reducing the number of rolls by one. In this arrangement I provide the top press 70 roll 8, and the bottom press roll 9, in the usual manner, and position a third or auxiliary press roll 10, also in pressure contact with the top press roll 8, retaining substantially equal diameters of all of the rolls and 75 substantially equal pressures between the rolls 8 and 9, and the rolls 8 and 10. In operation, the paper 11, travels on or is carried by the felt 6, first between the two press rolls 8 and 9, and then between the two press 80 rolls 8 and 10, and thence on to the press rolls 3, receiving roll 5, &c., as above explained. It will be observed that the felt carrier 6 is on one side only, and that is the under side of the paper at the point of application of the pressure of the pairs of rolls 8, 9, and 8, 10. It will thus be seen that by 85 this arrangement, I eliminate one of the press rolls of the ordinary Fourdrinier type of paper-making machine, without eliminating the number of press roll applications to the paper, and without requiring coöperating pairs of carrying felts at the points where the paper is subjected to the pressing action of the rolls. It will also be seen that 90 I retain substantial equality of diameters of the press rolls, and secure substantially uniform degrees of pressure between the rolls.

In Fig. 3, I show my invention as combining the press rolls 1, 2, and 3, of Fig. 1. 100 In this arrangement I provide the rolls 8, 9 and 10, as in Fig. 2, and position above the roll 8 a similar roll 12, so that the paper presses between the rolls 8 and 9, then between the rolls 8 and 10, and finally between the rolls 8 and 12. It will be seen 105 that the paper in effect, passes between three sets of press rolls, but in reality only four rolls are employed instead of six. It will be seen further that inasmuch as it is customary and the efficient practice to have a complete set of felt and felt rolls for each 110

pair of press rolls, I am enabled to eliminate all but one felt web and one set of felt rolls, though my invention is not to be limited in this respect as it is obvious that 5 independent felts may be employed if desired.

The respective press rolls 8, 10, and 12, may be driven by friction, or otherwise, and I have shown the same as being driven 10 by gears carried thereby, which mesh with a gear carried at one end of the roll 8. My invention, however, in its broad scope is not to be limited to this feature.

Having now set forth the objects and nature of my invention, and having described 15 a diagrammatic illustration of the same, to which, however, my invention as defined in the claims is not to be limited, what I claim as new and useful, and of my own invention, and desire to secure by Letters Patent, is,—

1. In a paper making machine, the combination with a pair of press rolls adapted to allow the paper to pass therebetween, and 25 positioned in contact with each other whereby one of said rolls is frictionally rotated by the other and an auxiliary press roll adapted to coöperate with one of said press rolls to form a second pair of press rolls 30 in the path of travel of the paper all of said rolls being of substantially the same diameter and mechanically operated means coöperating between said auxiliary press roll and one of said first mentioned press 35 rolls for rotating said auxiliary press roll.

2. In a paper making machine, the combination with a pair of press rolls adapted to allow the paper to pass therebetween, and positioned in contact with each other whereby 40 one of said rolls is frictionally rotated by the other and an auxiliary press roll

adapted to coöperate with one of said press rolls to form a second pair of press rolls in the path of travel of the paper all of said rolls being of substantially the same 45 diameter and mechanically operated means actuated by one of said press rolls for rotating said auxiliary press roll.

3. In a paper making machine, the combination with a pair of press rolls adapted 50 to allow the paper to pass therebetween, and positioned in contact with each other whereby one of said rolls is frictionally rotated by the other and a plurality of auxiliary press rolls each coöoperating with one of said first mentioned press rolls to form a series 55 of presses in the path of travel of the paper all of said rolls being of substantially the same diameter and mechanically operated means actuated by one of said press rolls 60 for rotating each of said auxiliary press rolls.

4. In a paper making machine, the combination with a pair of press rolls adapted to allow the paper to pass therebetween, and 65 positioned in contact with each other whereby one of said rolls is frictionally rotated by the other and a plurality of auxiliary press rolls each coöoperating with one of said first mentioned press rolls to form a 70 series of presses in the path of travel of the paper all of said rolls being of substantially the same diameter and independent gears actuated by one of said press rolls for rotating all of said auxiliary rolls.

In testimony whereof I have hereunto set my hand in the presence of the subscribing witnesses, on this 31 day of May A. D., 1916.

JAMES K. DARBY.

Witnesses:

NELLIE V. TUTTLE,
HORATIO C. CLAYPOOL.
